UNITED STATES PATENT OFFICE.

PAUL HARTMANN, OF BROOKLYN, NEW YORK, ASSIGNOR, BY DIRECT AND MESNE ASSIGNMENTS, OF ONE-HALF TO CHARLES L. EIDLITZ, OF NEW YORK, N. Y., AND ONE-HALF TO METROPOLITAN ELECTRIC MFG. CO., A CORPORATION OF NEW JERSEY.

FLUSH RECEPTACLE.

Application filed September 30, 1922. Serial No. 591,487.

While certain of the features of my invention are applicable to various types of electrical contact devices including rotary and snap switches and various forms of receptacles, my invention in general has especial application to so-called flush or base board receptacles which are set flush into the wall and provide outlets for the connection of electrical appliances.

10 An object of my invention is to simplify and reduce the manufacturing cost of such receptacles. Embodiments of my invention have materially fewer parts and are much more easily assembled than any other receptacle of which I have knowledge.

One feature of my invention has to do with the stationary contact member and particularly its means of support in the receptacle and its electrical connection with the binding post. In brief, I employ terminal members, that is, members attached through the binding posts to the main leads, which automatically interlock with the contact members, preferably by a spring or snap action, whereby through the simple operation of pressing the contact members in place they are connected to the leads and secured in the receptacle.

More particularly as applied to flush receptacles the contact member is disposed edgewise in a relatively narrow recess in the receptacle and has an integral spring leaf bent back from its front edge, while the terminal member extends through a passage in the receptacle body and has its inner end bent and engaging underneath the free edge of the spring leaf. The terminal member also has a part engaging the receptacle body so as to be held in place so long as the spring leaf exerts its resilient pressure on the inner end of the terminal member. The binding post preferably screws into the outer end of the terminal member and may cooperate to hold the parts in place.

45 My invention is applicable for either single or duplex receptacles, and for both the so-called parallel and tandem slots for the attachment plug blades. The contact terminals for the plug blades are also preferably integral with the metallic strip which serves as the bus contact member, being spring contact leaves formed by bending back one or more extensions on the inner edge thereof. These contact terminals or

leaves are preferably somewhat higher than the one with which the binding post terminal member engages, and the recess is made somewhat deeper opposite the slots for the plug blades, thereby forming what I term contact chambers to accomodate these spring 55 terminals. The slots for the plug blades enter the contact chambers at the side thereof on which are the spring contact leaves, thereby facilitating the admission of the plug blades into the slots while assuring 60 good contact through the lateral resilient pressure of the leaves against the blades.

For a receptacle having both parallel and tandem slots, each of the bus contact members is provided with two spring contact 70 leaves for the plug blades bent back on opposite sides of the strip so that one will be brought in register with one of the parallel slots and the other in register with one of the tandem slots. If the slots are at an 75 angle to each other in the face of the receptacle, the terminal leaves are disposed at a corresponding angle. If the bus member is designed for a single receptacle the contact spring leaf or leaves are on one end 80 only, while for a duplex receptacle they are duplicated on the other end.

A noteworthy feature of my invention is the fact that the metallic strip forming the bus or stationary contact member is so cut 85 that the grain of the metal runs transversely of the strip, and since the extensions forming the spring leaves are on one longitudinal edge, the bends of the leaves are all across the grain, and hence they will not 90 break from the continual flexing to which they are subjected by insertion of the plug blades.

My invention includes many other features as will appear from the following description. I shall now describe the illustrated embodiments of my invention and shall thereafter point out my invention in claims:

Fig. 1 is a face or plan view of the insulating body member of a duplex receptacle embodying my invention.

Fig. 2 is a side elevation of the same;

Fig. 3 is a rear face or plan of the same;

Fig. 4 is a longitudinal section taken on line 4—4 of Figures 1 and 3, of the complete assembled receptacle as it is disposed in the wall;

Fig. 5 is a transverse section of the parts shown in Figure 4, taken on line 5—5 of Figure 4, and showing the contact plug inserted.

5 Fig. 6 is a transverse section of the body member shown in Figures 1, 2 and 3 taken on line 6—6 of Figure 1, and also showing the contact and terminal elements inserted in place;

10 Fig. 7 is an end view of the body member shown in Figures 1, 2 and 3;

Figs. 8 and 9 are details in side elevation and in end view, respectively, of one of the bus contact members used in this type of receptacle;

Fig. 30 is a transverse section on the broken line 30—30 of Figure 29;

65 Fig. 31 is a detail in plan of one of the bus contact members in this latter type of receptacle.

While the description of my invention will

be confined to flush receptacles, it will be understood that so far as my invention is applicable to other electrical contact devices, it is not limited to flush receptacles.

The receptacle shown in Figures 1 to 11, 70 inclusive, is a duplex receptacle, that is, one provided with slots for two outlet plugs, and the slots in this form of receptacle accommodate only plugs having parallel blades. The slots are designed for so-called selective 75 polarity plugs, that is, plugs having one of their blades wider than the other.

The body member 1 is preferably molded and is composed of some suitable insulating material, such as porcelain. It is a unitary 80 and generally oblong member with rounded corners and has its front face shaped to receive a cover plate 2. The two portions of the face, 1^a and 1^b, in which the slots 3, 4, 5 and 6 for the plug blades are formed, are 85 generally circular in outline with flattened sides and raised above the rest of the face, while the cover plate is provided with corresponding openings so that the faces 1^a and 1^b are flush with the face of the cover plate 90 when the latter is in place. An intermediate neck portion 1^c on the front face is provided with a square transverse hole 1^d in which is a suitable assembly pin 7 having a threaded opening in its upper end in which a screw 95 engages and holds the cover plate in place. This assembly pin projects through the lower end, as shown in Figures 2 and 4, for the purpose of being riveted or otherwise caught over the strap in the final assembly of the 100 receptacle, as appears in Figure 4 and will be hereinafter described. The assembly pin 7 is shouldered intermediate of its length so as to limit its inward movement in the opening 1^d. On each side of the neck portion 1^c 105 the face is substantially cut down to provide the portions 1^e and 1^f which are provided with holes 8 and 9 for binding posts.

At their inner ends, these surface portions 1^e and 1^f terminate in slots or passages 110 10 and 11, respectively. On each side the body member is provided adjacent the portions 1^e and 1^f with a vertical recess, as shown, to accommodate the main lead wires.

In its rear face the body member 1 is 115 provided with two relatively narrow longitudinal recesses 12 and 13, the central portion of which recesses connects with the passages 10 and 11, respectively, while the end portions are made somewhat deeper 120 than the intermediate portion to provide contact chambers which connect with the slots 3, 4, 5 and 6.

In each of the slots 12 and 13 is disposed a bus contact member, such as shown in 125 detail in Figures 8 and 9. This is composed of suitable resilient conductive material, such as phosphor bronze, and is a thin strip 14, provided along its upper edge with three integral tongues or extensions 130

15, 16 and 17. The strip is so cut from the metal that the grain runs transversely of its length, as indicated in Figure 8, and the three extensions 15, 16 and 17 are bent back substantially parallel with the face of the strip 14, so as to form spring contact leaves. The danger of the metal breaking at these ends is minimized by the fact that all of the bends are across the grain of the metal. The bend of the intermediate contact leaf 16 is nearer the top edge of the strip 14 than is that of the leaves 15 and 17. In other words, the leaves 15 and 17 are somewhat higher than is the intermediate leaf 16, so that in side elevation the member presents an approximation to a U-shape. Due to this fact, when the members 14 are inserted in the slots 12 and 13, the intermediate bend 16 rests against the bottom of the shallow portion of the slot, while the higher contact terminals 15 and 17 extend up into the contact chambers or deeper portions of the recesses and register with the slots 3, 4, 5 and 6, as shown in Figure 4. The bus members are disposed edgewise in the slots against the inner faces thereof with the spring contact leaves on their outer sides. The slots 3, 4, 5 and 6 for the plug blades open into the contact chambers on the outer sides thereof so that the plug blades engage the outer faces of the contact spring leaves. This is illustrated in Figure 5 where the plug blades 18 and 19 of the plug 20 are shown in the slots 5 and 6 in electrical contact with the spring leaves 17.

To secure the bus contact members in their respective recesses as well as to electrically connect them to the lead wires, angle members 21 such as shown in detail in Figures 10 and 11, are used. One arm of these angle members lies upon the faces 1^e and 1^f and is provided with a screw-threaded opening into which the binding post engages. This is shown particularly in Figure 6 where the binding post 22 is in place in the outer arm of the angle member 21 and is received in the hole 8 in the body member. The lead wire 23 is clamped by the binding post against the angle member 21.

The other arm of the angle members 21 extend into the slots 10 and 11, respectively, as shown in Figures 4 and 6. At its inner end this arm of the angle members is bent inwardly to form a hook-member, as shown, and this hook member engages underneath the free edge of the contact leaf 16. In assembling the parts, it will, therefore, be seen that it is only necessary to get the angle member in place with the binding post in the hole 8 or 9 and the inner arm disposed in the slot 10 or 11, and then to press the bus contact member upward until the spring leaf 16 snaps over the bent inner

end of the arm of the angle member 21. By reason of the resilient pressure of the spring leaf 16 against the inner arm of the angle member 21, both members are held in place.

The device is completed by placing a strip of fibre or other insulating material 24 in the shallow recess 25 provided in the rear face of the body, thereby covering both slots 12 and 13, and then securing in place a metal strap 26 which passes around three sides of the body in suitable grooves cut therefrom and has outwardly turned ears which are provided with holes for screws for attachment to the wall in the usual way. The assembly pin 7 passes through a hole in both the fibre strip 24 and the strap 26 and then has its outer end riveted over, as shown in Figure 4, to secure all of the parts together, or if desired, the projecting end of the pin 7 may be screw-threaded and a suitable nut may be screwed thereon.

In Figures 21 to 28 there is shown a single receptacle, that is, one providing an outlet for one attachment plug only. There are two pairs of slots in the front face of the receptacle, the slots 27 and 28 being one pair for parallel blades, and the slots 29 and 30 being the other pair arranged for tandem blades. The receptacle body 31 is molded of porcelain or other suitable insulating material and is provided in its rear face with the two longitudinal recesses 32 and 33. In the outer end of the recess 32 opens a slot 34 from one corner of the front face, and in the outer end of the slot 33 opens a slot 35 from the diagonally opposite corner of the front face. Adjacent the slots 34 and 35 are the holes 36 and 37 for the binding posts, the corner portions which include the binding post holes and the slots 34 and 35 being depressed below the general level of the front face of the receptacle, as are the corresponding portions 1^e and 1^f in the construction shown in Figure 1. The slots 28 and 29 also open into the recess 33 and the slots 27 and 30 also open into the recess 32. The three slots in each recess are staggered, as shown, thus providing the proper disposition for the four plug blade slots. Also the portion of the recesses into which the plug blade slots enter is deeper than is the portion into which the slots 34 and 35 open, thus providing the contact chambers, as in the preceding construction.

The bus contact member used with this single receptacle is shown in detail in Figures 27 and 28, and consists of a thin strip 38 of suitable metal with the spring leaf 39 at one end for engagement with the angle member 21, and the two contact spring leaves 40 and 41, one bent down on one side of the strip and the other on the other side of the strip. By reason of this construction, when the bus member is inserted in the slot 32,

the contact leaf 39 is in register with the slot 34 in position to be engaged by the inner end of the angle member 21, as shown in Figures 24 and 25. Also the spring leaf 40 is in register with the slot 30 and the spring leaf 41 is in register with the slot 27. Similarly when the bus member is inserted in the slot 33 the spring leaf 39 is in register with the slot 35, while the spring leaf 40 is in register with the slot 29, and the spring leaf 41 is in register with the slot 28. The plug 20 with parallel blades is shown in position in Figure 26, the blade 18 engaging with spring contact leaf 41 of the one bus member and the blade 19 engaging with spring contact leaf 41 of the other bus member. The bottom of the recesses are closed by a suitable insulating strip 42 of fibre or other suitable material and the strap 43 passes around the member on three sides in the usual way. This strap automatically locks to the body member through struck-out spring tongues or clips which catch over the bottom of two grooves in the end walls, as indicated in dotted lines in Figure 24, and as described and claimed in my co-pending application Serial No. 591,488 filed September 30, 1922.

In Figures 12 to 20 is shown a duplex receptacle in each end of which are the two pairs of slots to accommodate either parallel or tandem blades on an attachment plug. The slots 44 and 45 on the one end, and the slots 46 and 47 on the other end are for the tandem blades, while the slots 48 and 49 on the one end and the slots 50 and 51 on the other end are for parallel blades. With this exception, the face and shape of the receptacle body 52 are substantially like those of the receptacle shown in Figure 1. The recesses 53 and 54 in the rear face of the receptacle are shaped in this instance to take the bus member which is shown in detail in Figures 18, 19 and 20. In this case the ends of the strip 55 are turned at right angles to the general line of the strip, and one end has the oppositely turned spring leaves 56 and 57, while the other end has similarly oppositely turned spring leaves 58 and 59. Intermediate of its ends, the bus member is provided with the spring leaf 60 which will register with the slots 10 and 11 when disposed in the respective grooves 54 and 53.

It will be seen that when the bus member 55 is disposed in the slot 54, the spring leaf contact 58 will be in the contact chamber registering with the slot 45, while the leaf 59 will register with the slot 49, the leaf 56 will register with the slot 47 and the leaf 57 will register with the slot 51. Similarly when the bus member is in the recess 53, the leaf 60 will register with the slot 11, the leaf 57 will register with the slot 48, the leaf 56 will register with the slot 44, the leaf 59 will register with the slot 50 and the leaf 58 will

register with the slot 46. The bus members will be held in place and connected to the binding post and lead wires through the angle terminal members 21 as described in connection with the construction of Figures 70 to 11 and as indicated in Figure 16.

In Figures 29 to 31 is shown a construction of a duplex receptacle having both parallel and tandem slots differing somewhat from the construction shown in Figures 12 to 20, 75 inclusive. In this case the parallel slots merge into and are disposed at an angle to the tandem slots. The parallel slots on the one end are numbered 61 and 62, and on the other end are numbered 63 and 64, while 80 the tandem slots are numbered 65 and 66 on the one end and are numbered 67 and 68 on the other end. It will be seen that the line of the tandem slots is at an angle of about 37½° to the line of the parallel slots. The 85 recesses in the rear face of the receptacle 69 are shaped to take a bus member like that shown in Figure 31. This bus member 70 has the intermediate spring leaf 71 for registering with the slots 10 and 11 and has the 90 spring leaves 72 and 73 for registering with the parallel slots, while the spring leaves 74 and 75 are bent at an angle of about 45° to the line of the bus member in order to register with the tandem slots. It will be seen 95 that if this bus member 70 is disposed in the upper recess, the spring leaves 72 and 73 will register with the slots 61 and 62, while the spring leaves 74 and 75 will register with the slots 65 and 67. To place the bus member in 100 the lower recess, it is turned end for end and it will be seen that the spring leaves 75 and 74 will register with the recesses 66 and 68, while the spring leaves 73 and 72 will register with the slots 62 and 64. 105

It will be noted that in all of the illustrated duplex constructions the selective polarity parallel slots are reversed in their positions in the two ends of the receptacle, that is, where the wide slot, e. g., communicates with one bus contact member on one end, it communicates with the other one on the other end. The advantages of this arrangement are pointed out and the construction is claimed in my copending application 110 Serial No. 591,489 filed September 30, 1922. 115

It is obvious that various modifications may be made in the constructions shown in the drawings and above particularly described within the principle and scope of my 120 invention.

I claim:

1. A flush receptacle comprising a body of insulating material interiorly recessed and provided with both a slot for a plug blade 125 and with a passage communicating with the recess, a contact bus member in the recess having a contact terminal registering with the slot, and a terminal member extending through the passage and resiliently inter- 130

locking with the contact bus member and having a part coacting with the body to hold the contact bus member and terminal member in place.

2. A flush receptacle comprising a body of insulating material interiorly recessed and provided with both a slot for a plug blade and with a passage communicating with the recess, a contact bus member in the recess having a contact terminal registering with the slot, and a unitary terminal angle member having one arm extending through the passage and resiliently interlocking with the contact bus member and the other arm coacting with the body to hold the contact bus member and angle member in place.

3. A flush receptacle comprising a body of insulating material having in its rear face an elongated recess and both a slot for a plug blade and a passage leading from the front face to the recess, a flat contact bus member disposed in the recess in a plane parallel with the slot, a binding post, and a conductive angle member having one arm exposed and engaging the binding post and the other arm extending through the passage and resiliently interlocking with the contact bus member.

4. A flush receptacle comprising a body of insulating material having in its rear face an elongated recess and both a slot for a plug blade and a passage leading from the front face to the recess, a flat contact bus member disposed in the recess in a plane parallel with the slot and having two resilient outstanding contact terminals, one registering with the slot and the other with the passage, a binding post, and a conductive angle member having one arm exposed and engaging the binding post and the other arm extending through the passage and hooking with its inner end underneath the adjacent contact terminal.

5. A flush receptacle comprising a body of insulating material having in its rear face an elongated recess and both a slot for a plug blade and a passage leading from the front face to the recess, a flat metallic contact bus member disposed edgewise in the recess in a plane parallel with the slot and having a reversely bent contact spring leaf integral with the inner edge of the bus member and registering with the slot, a binding post, and a conductive member extending through the passage and mechanically engaging the spring leaf and electrically connecting the contact bus member and binding post.

6. A flush receptacle comprising a body of insulating material having in its rear face an elongated recess and both a slot for a plug blade and a passage leading from the front face to the recess, a flat metallic contact bus member disposed in the recess in a plane parallel with the slot and having

two reversely bent leaves registering respectively with the slot and passage, a binding post, and a conductive member extending through the passage and engaging the binding post with its outer end and hooking underneath the adjacent leaf with its inner end.

7. A flush receptacle comprising a body of insulating material provided interiorly with an elongated recess and having both a slot for a plug blade and a passage leading from the front face to the recess, a flat metallic contact bus member disposed edgewise in the recess in a plane parallel with the slot, and having a reversely bent contact spring leaf integral with the inner edge of the bus member and registering with the passage and a terminal member extending through the passage and engaging the rear edge of the spring leaf of the contact bus member in interlocking relation.

8. A flush receptacle comprising a body of insulating material provided in its rear face with an elongated and relatively narrow recess including at least one contact chamber deeper than the rest of the recess, the body being also provided in its front face with a slot for a plug blade entering the bottom of the contact chamber at one side thereof and with a passage for a binding post connecting member leading from its front face to the shallower part of the recess, a metallic contact bus member disposed flat against one side wall of the recess and having at its end on its outer face a contact terminal extending into the contact chamber and having a laterally yielding part in register with the said passage, and a binding post connecting member extending through said passage and engaging the laterally yielding part and coacting therewith to hold both the said member and contact strip in place.

9. A flush receptacle comprising a body of insulating material provided in its rear face with an elongated and relatively narrow recess having at least one end an angular contact chamber deeper than the rest of the recess, and provided in its front face with two angularly disposed slots for plug blades communicating with the contact chamber and with a passage for a binding post connecting member leading from the front face to the shallower part of the recess, a metallic contact strip disposed flat against one side wall of the recess and having at its end two angularly disposed contact terminals extending into the contact chamber in register with the said slots and having a laterally yielding part and coacting therewith to hold both the said member and contact strip in place.

10. An electrical contact device comprising a body of insulating material provided in its rear face with a groove and having

- a passage therethrough from the front face to the groove, a contact bus member disposed in the groove and an angle shaped terminal member bearing with one leg against the front face of the body and extending with its other leg into the passage, the bus member and said other leg being shaped to interlock by relative movement of the two members toward each other.
- 10 11. An electrical contact device comprising, in combination with the lead wires, a body of insulating material provided with a passage therethrough, a stationary contact member bearing against the rear side of the body and having a resiliently yieldable projection extending into the passage, and a terminal member connected to one of the lead wires and bearing against the front side of the body and extending into the passage and having a hook member on its inner end 20 engaging underneath said yieldable projection.

In witness whereof, I hereunto subscribe my signature.

PAUL HARTMANN.
